UNITED STATES PATENT OFFICE.

GEORGE S. CALDWELL, OF AUBURN, NEW YORK.

DESIGN FOR A HANDLE FOR SLEIGHS, DOORS, &c.

SPECIFICATION forming part of Design No. 19,561, dated January 7, 1890.

Application filed December 6, 1889. Serial No. 332,854. Term of patent 7 years.

To all whom it may concern:

Be it known that I, GEORGE S. CALDWELL, of Auburn, Cayuga county, New York, have invented and produced a new and original 5 Design for Handles for Sleigh and Wagon Bodies, Doors, Drawers, &c., of which the following is a specification, reference being had to the accompanying drawings, in which—

Figure 1 represents a side and Fig. 2 a top 10 view of a handle showing my design.

My design exhibits a central elongated portion A, at an angle to which and at opposite ends thereof appear the symmetrically-placed 15 portions B and C. Extending from about the meeting-points of the parts B and C with the

part A, and symmetrically disposed in relation thereto, appear projections D, each having on one edge a curve E and an inclined portion F, and on the other edge a curve G and outwardly-rounded portion H. The entire handle may appear longitudinally curved, as shown in Fig. 2.

I claim—

The design for a handle for sleigh and wagon bodies, doors, drawers, &c., substantially as herein shown and described. 20 25

GEORGE S. CALDWELL.
